CLAIM

The ornamental design for a handlebar grip, as shown
and described.

DESCRIPTION

FIG. 1 is a perspective view of a handlebar grip showing
my new design;

FIG. 2 is a side elevational view thereof, the opposite
side being a mirror image of that shown;

FIG. 3 is a left end elevational view thereof; and

FIG. 4 is a right end elevational view thereof.

FIG. 1

FIG. 2

FIG. 3

FIG. 4
